LENS GRINDING MACHINE OR THE LIKE

Lindsay M. Ball, Medford, and George L. Guaraldi, Chelmsford, Mass., assignors to Bond Research Laboratories, Inc., Somerville, Mass., a corporation of Massachusetts

Filed Aug. 21, 1968, Ser. No. 13,223

Term of patent 14 years

Int. Cl. D15—05

U.S. Cl. D37—1

Fig. 3

Fig. 1

Fig. 2

Fig. 4

FIG. 1 is a perspective view of our new design for a lens grinding machine or the like with portions of the spindle support omitted for ease of illustration;

FIG. 2 is a front elevation of the machine showing the spindle support;

FIG. 3 is a top plan of the machine; and

FIG. 4 is a side elevation as seen from the right side of FIG. 3.

We claim:

The ornamental design for a lens grinding machine or the like, substantially as shown and described.
